UNITED STATES PATENT OFFICE

HARRY E. BUTTS, OF SANDUSKY, OHIO, ASSIGNOR OF ONE-HALF TO EDMUND L. STEWART, OF SANDUSKY, OHIO

TROLLEY FOR ELECTRIC CARS

Application filed May 16, 1930. Serial No. 453,028.

This invention relates to trolleys for electric cars, and has special reference to an improved construction of trolley pole and fork or harp, and contact roller mounted therein.

The main object of the invention is to provide a trolley for electric cars employing as a contact member a roller in place of a wheel, which is free to rotate on its own axis, as well as free to have yielding up and down movements, whereby a reliable contact between the trolley and trolley wire will always be maintained.

A further object of the invention is to provide a novel construction of the fork or harp in which the contact roller is mounted, by means of which free and easy movements of the character described of the roller are ensured, and the roller arranged in such manner that under all normal conditions of service, the trolley can not jump the trolley wire even in the event of the contact roller momentarily moving out of engagement therewith.

The invention consists of the features of construction, combination and arrangement of parts, hereinafter fully described and claimed, reference being had to the accompanying drawings, in which:—

Fig. 1 is a view in side elevation, with parts broken away, of a trolley constructed in accordance with my invention.

Fig. 2 is a vertical transverse section through the same on line 2—2 of Fig. 1.

Fig. 3 is a perspective view of the bearing block.

Referring now more particularly to the drawings, 1 designates the trolley pole, and 2 the trolley head or frame, which latter has a base or stem portion 3 provided with a socket 4 to receive the upper end of the pole 1 to which the trolley head or frame is connected by suitable fastening means 5.

The trolley frame or head has a harp or fork portion comprising independent side members or plates 6 and 7. One of these plates, as the plate 6, may be integral with the base or stem 2 or permanently fixed thereto, while the other plate 7 is detachably con-

nected with the plate 6, as by means of fastening bolts or screws 8.

The opposed inner faces of the side members or plates 6 and 7 are recessed to cooperatively provide a chamber 9 having a bottom portion 10 closed except for communication with a guide opening 11 extending therefrom downwardly through the upper rear portion of the base or stem 2. The chamber 9 is open at its upper end and communicates with a guide channel 12 formed by and between upper portions 13 of the members 6 and 7 of reduced thickness. The channel 12 is designed to receive the trolley wire and permit engagement of the trolley therewith and the parts 13 serve as side guards or flanges to hold the trolley head in engagement with the trolley wire and from lateral disconnection from the trolley wire, as hereinafter fully described.

The side walls of the recesses of the respective plates 6 and 7 forming the chamber 9 serve as guides for a vertically movable bearing member or block 14. This block is provided in its upper face with a semi-circular bearing recess or cavity 15 to receive a circular contact roller 16, and the upper face of the block is also provided with a countersink or chamber 17 arranged at right angles to the recess 15 to receive a suitable lubricant to keep the bearing and contact roller suitably lubricated.

The block 14 is mounted upon the upper end of a guide rod or stem 18 projecting downwardly through the chamber 9 and the guide opening 11 to center and guide the block 14 in its movements, and encircling that portion of the rod arranged in the chamber 9 in a coiled cushioning and pressure spring 19 which has its base on the bottom wall 10 of said chamber and is seated at its upper end in a recess 20 in the bottom of the bearing block. This spring permits the bearing block 14 to move downwardly in its guideway to accommodate itself to variations in the level of portions of the trolley wire and to undulations therein, while at all times yieldingly forcing the block upward to maintain the contact roller 16 in engagement with the trolley wire.

The roller 16 is fitted to turn in the bearing recess 15 of the block and in retaining or stop recesses 21 of partially circular form in the flanges 13, which recesses 21 communicate with the recesses forming the chamber 9 and thus permit free downward movement of the roller 16 while providing stop surfaces against which the uppermost surfaces of the ends of the roller may bear to limit the upward movement of the roller to a point below the level of the extreme upper portions of the guide flanges 13. Thus it will be understood that at all levels of the contact roller 16 the trolley wire will be received in a channel 12 of some material depth and formed by guard flanges 13 which will operate to prevent, under all normal conditions, any lateral displacement of the trolley from the wire, even when the trolley encounters sharp curves and lateral deflections in the wire.

By the use of the contact roller 16, which, unlike the trolley wheel, does not revolve upon an independent axis, but upon its own axis and is also slidably mounted for vertical movement in the trolley head, provision is made for a free and easy rolling contact between the trolley and the trolley wire and for a free and unobstructed cushioned vertical movement of the contact roller in a vertical plane, so that it will under all normal conditions maintain contact with the wire, while disengagement of the trolley head from the wire, even in the event of temporary movement of the head out of contact with the trolley wire, will be prevented by the side guards or flanges 13 which will at the same time maintain electrical conducting connection with the wire. Hence the frequent jumping of the trolley out of contact with the wire, which occurs with trolleys of ordinary construction, will be prevented, and damage to the trolley wire and its supports correspondingly reduced, as well as the annoyances and inconveniences to traffic caused by displacement of the trolley from the wire. Furthermore, as the roller 16 will rotate at all times freely in contact with the wire, in all positions of said roller relative to the trolley head, undue wear and tear upon the trolley wire which would be caused by sliding contact of the roller therewith will be effectually obviated. The construction described is also advantageous in enabling the trolley to be easily, conveniently and cheaply constructed and its parts assembled for use and disassembled for purpose of cleaning and repairs.

Having thus fully described my invention, I claim:—

1. In a trolley, a trolley head comprising a pair of vertically divided members having their inner faces formed to provide a vertical chamber and guideways and a wire receiving channel above and communicating with said chamber and having guard flanges at op-

posite sides thereof, a spring supported bearing in said chamber, and a contact roller in guided connection with the members of the head and journaled for rotation upon said roller.

2. In a trolley, a trolley head including a pair of spaced members provided upon their inner sides with recesses forming a chamber having guide walls and with guard flanges providing a trolley wire receiving channel above said chamber and communicating therewith, said flanges having bearing and retaining recesses in their inner faces, a bearing block mounted in said chamber and guided by the guide walls thereof and provided with a bearing recess, means yieldingly supporting said bearing block, and a contact roller mounted in the bearing recess of the bearing block and engaging and limited in upward movement by the bearing and retaining recesses in the flanges.

3. A trolley comprising a trolley head formed of detachably connected members, said members having their inner faces recessed to provide a guide chamber and guideways and terminating at their upper ends in guide flanges forming a trolley wire receiving channel and communicating with said chamber, the inner surfaces of the flanges being provided with guide and retaining recesses, a bearing block movable vertically in said chamber and guided by the guide walls thereof, said block having a bearing recess in its upper face, a contact roller journaled in the bearing recess in the block and having its end portions engageable with said guide and retaining recesses, a stem connected with the block and slidably mounted on the head, and a coiled spring in the chamber and surrounding the head between the block and bottom of the chamber.

In testimony whereof I affix my signature.
HARRY E. BUTTS.
